CLAIM

The ornamental design for an electronic dog collar, as shown and described.

DESCRIPTION

FIG. 1 is a front perspective view of an electronic dog collar; FIG. 2 is a front view thereof; FIG. 3 is a rear view thereof; FIG. 4 is a right side view thereof; FIG. 5 is a left side view thereof; FIG. 6 is a top view thereof; and, FIG. 7 is a bottom view thereof.

The structural features depicted by broken lines in the drawings have been shown for the purpose of illustrating portions of the electronic dog collar that form no part of the claimed design.

1 Claim, 5 Drawing Sheets
